MOP CLEANER

Forrest G. Clipper, San Jose, Calif.

Application October 19, 1935, Serial No. 45,771

1 Claim. (Cl. 15—142)

The present invention relates more particularly to means for cleaning dust mops.

After a dust mop has been used and filled with dust, lint, and other foreign matter which it has picked up from the floor, it is common practice to clean the same by shaking it out of a window or door, merely transferring the said foreign material from the floor to the air out of which it again settles but in a different place.

It is the object of the present invention to provide means whereby the dust may be quickly and easily removed from the mop within the building and without releasing any of it into the air whereby it may again settle upon the floor and furniture.

It is also an object of the invention to provide a means of the character indicated that will be economical to manufacture, simple in form and construction, easily transported from one room to another, that consists of few parts, and that is strong, durable, light in weight, easily emptied, and highly efficient in its practical application.

In the drawing:

Figure 1 is a perspective illustration of a device embodying my invention, a part being broken away.

Figure 2 is a sectional view on line 2—2 of Figure 1.

Figure 3 is a sectional view on line 3—3 of Figure 1, with parts broken away.

Figure 4 is a detail section through a portion of the door and case at 4—4 of Figure 1.

In the particular embodiment of the invention herein disclosed, I show at 1 a chamber defined by an elongated casing 2 that presents an oval configuration in transverse cross-section. The casing is formed of a single sheet of sheet metal bent into the form indicated with its two longer edges approaching each other to form a slot 3. The casing is supported by legs 4 with the slot 3 uppermost and disposed in a horizontal plane. The slot 3 is normally closed by rubber lips as 5 and 6 seated in opposed relation to each other in sockets as 7 and 8 in casing 2 and fixedly held against displacement by plates 9 and 10. These lips normally contact each other along their opposing edges as at 11.

The casing 1 is further defined by a fixed closure 12 at one end, this end being fitted with a handle shown in dotted lines at 13 and extending crosswise of the said end.

The lower portion of the other end of the casing 2 is fitted with a door 14 swingably mounted on a rod 15 extending horizontally across the end 55 of the casing. When the casing is tipped up on

this end the door 14 will automatically swing open for the discharge of the contents of the casing. To hold the door in a normally closed position it is fitted with a spring latch 16 movable into engagement with a keeper 17.

Spaced a distance above the rod 15, and in parallel relation thereto, is another supporting rod 18. On this rod 18 is swingably mounted an upper door 19. The door 19 extends below the rod 18 to normally fill and close the space between rods 15 and 18 as at 20, and this portion of the door is weighted as at 21. As herein disclosed the door 19 is built up of two pieces of sheet metal laid flat one against the other and clamping a peripherally disposed rubber strip as 22. The edge of the metal portion of the door is spaced from the casing 1 and the rubber strip extends outwardly therefrom as at 23 to slightly overlap a similar strip of rubber 24 seated in a socket 25 formed in casing 2 as shown. The result of this construction is that the largest portion of the door lies above the rod 18, and the door may be swung freely in either direction, even into a horizontal position as indicated at 26, but it will always return to its normal vertical position with the rubber strips 24, 25 contacting and preventing the escape of dust from the interior of the casing.

Mounted within the casing is a horizontally disposed grate 27. This grate extends the full length and width of the casing, and as herein disclosed is placed just below the level of the bottom of door 19, with its cross bars 28 extending transversely of the casing as shown.

Bumper rods are fixedly mounted in the casing as at 29, and so positioned that the door 19 may swing freely but will be protected against movement of the mop when being cleaned as hereinafter described. The device is fitted with handles as at 30, one on each side of the slot 3, but movable to form a space between them 40 through which a mop handle may pass.

In using the device it is only necessary to pass the handle of the mop between the lips 5 and 6 with the head of the mop entering the casing by swinging the door 19 inwardly. When the mop head is entirely within the casing the door 19 will automatically close. The mop head is then lowered upon the grate 27 and moved back and forth thereover thereby extracting the dust therefrom and depositing it in the bottom of the chamber 1. The lips 5, 6 permit the handle of the mop to be moved back and forth as required during this operation, yet the dust liberated from the mop is confined within the chamber 1.

When the cleaning is accomplished and the 55

mop removed the casing may be emptied by releasing the catch 16 and tipping the casing by means of handle 13, the door 14 then automatically swinging open and permitting the contents of the casing to flow out.

The door 19 swings in a doorway 31, and the upper end of the doorway has open communication with the slot 3 at 32 so that when a mop head is moved into or out of the casing the mop handle will pass freely into or out of the slot 3 and between the rubber lips 5 and 6. These lips 5-6 will, of course, automatically close around the mop handle as it moves back and forth between them and effectually prevent the escape of dust from the casing through slot 3.

It is to be understood, of course, that while I have herein shown and described but one spe-

cific embodiment of the invention, changes in form, construction, and method of assembly and operation may be made within the scope of the appended claim.

I claim:

A mop cleaner comprising, an elongated casing having a member supported therein upon which a mop may be rubbed, and having a slot formed therein above said member through which the handle of a mop may be moved, said casing being closed at one end and having a doorway formed in the other end above said member and communicating with said slot, and an automatically closing freely swinging door with a free edge directed upwardly toward said slot, in said doorway.

FORREST G. CLIPPER.
